MIST TRAPPING SHIELD FOR LENS SURFACING MACHINES

Filed July 22, 1949

FIG. 2

INVENTOR.
BY HAROLD W. KOSBAB
H.W. Kosbab

UNITED STATES PATENT OFFICE

2,579,193

MIST TRAPPING SHIELD FOR LENS
SURFACING MACHINES

Harold W. Kosbab, Irondequoit, N. Y., assignor to
Bausch & Lomb Optical Company, Rochester,
N. Y., a corporation of New York

Application July 22, 1949, Serial No. 106,248

2 Claims. (Cl. 51—131)

1

This invention relates to improvements in high speed surfacing machines such as lens grinders and polishers and the like and relates more particularly to means for trapping the mist or atomized liquid abradant that is produced when the liquid strikes the rapidly rotating tool.

When using diamond charged tools for lens grinding, the tool spindles are rotated at relatively high speeds of about 3000-4000 R. P. M. The tools are carried at the upper ends of vertical spindles and a liquid coolant is supplied to the surface of the tool as the lens is held in grinding contact therewith. Since the tool is rotating at a high speed, the liquid is thrown off the periphery of the tool by centrifugal force and is atomized. The atomized particles form a mist or fog that rises up and wets the arms and body of the operator as well as the overhanging parts of the machine.

It is, therefore, an object of this invention to provide novel means for trapping the mist that is produced as the liquid coolant is thrown off the tool and against the side of the splash pan in surfacing machines of the high speed type.

It is a further object to provide such a device which is efficient in operation, does not limit the usefulness of the surfacing machine, and affords easy demountability of the surfacing tool without disturbing the mist trapping means.

A further object is to provide a mist trapping shield for a high speed surfacing machine which is self-locating, easily demountable from the machine without the use of tools and which expedites the cleaning of the splash pan.

Further objects and advantages will be apparent from the novel details of construction and combination of parts as described hereinafter and shown on the accompanying drawing in which:

Fig. 1 is a substantially vertical sectional view of a lens surfacing machine embodying one form of my invention.

Fig. 2 is a perspective view of a section of the mist trapping shield shown in Fig. 1, and

Fig. 3 is a fragmentary sectional view of a modified mist trapping shield.

A lens surfacing machine is shown generally at 10 in Fig. 1 having a stationary splash pan 11, the bottom of which is in the form of a reservoir 11' for receiving a coolant liquid 12. The pan 11 rests on a stand of suitable design or may be attached to a machine base, not shown, which houses mechanism, such as a motor, coolant pump, or other auxiliary apparatus required by the surfacing operation. Through a central opening 13 in the bottom of the pan 11 there projects

5 a high speed spindle 14, the lower end of which is connected to suitable motive power such as an electric motor, not shown. On the upper end of the spindle 14, a surfacing tool 15 is demountably secured by any suitable means such as the tapered, frictional connection 16. A jet of liquid coolant 20 is supplied to the tool 15 by means of a nozzle 17 which is connected by a valve 18 and a supply pipe 19 to a suitable coolant pump or 10 gravity tank connected with the reservoir 11' so as to provide a circulating system such as is well known in the art.

15 A lens blank is shown at 21 in operating position on the tool 15, the blank being secured by a suitable adhesive pitch on a lens block 22. The lens blank 21 is held against the tool 15 by a pressure pin 23 having a pointed end which is seated in a conical recess 24 in the back of the lens block 22. Pressure is manually transmitted to the pressure pin 23 by the operator through a swivelled operating lever 25 connected by a frictional lock 26 to a head 27 through which the pin 23 projects.

20 According to this invention, a mist trapping shield 28 is provided inside the pan 11 to prevent the atomized liquid or mist, which is produced when the coolant 12 is centrifugally thrown off the tool 15 against the side of the pan 11, from rising out of the pan and onto the operator or parts of the machine. The shield 28 is preferably built in the form of a flat annular plate which is inclined somewhat towards the center. A central circular opening 29, provided in the shield 28, should be large enough to permit easy 25 removal of the tool 15 therethrough. The opening 29 should also be large enough to allow ample operating clearance between the pressure pin 23 and the shield 28 when the pin is swung to extreme sideward position when grinding a strong 30 curvature on the lens as shown in Fig. 1. Moreover, the diameter of the opening 29 must be controlled within limits to provide a maximum effectiveness of mist suppression while at the same time obtaining the above-mentioned clearance requirements.

35 It has been found that the diameter of the opening 29 may vary from about 8-12 inches and that the edge of the opening 29 should be about 1-3 inches above the tool 15. In one successful 40 embodiment of the invention the splash pan 11 is about 10 inches deep and has an inside diameter of about 17 inches while the shield opening 29 has a diameter of about 10 inches and the edge of the opening 29 is located about 1½ inches 45 above the tool 15. It is to be understood that 50

these dimensions are not critical and that they need only be such as to afford easy access to the tool and allow ample operating clearance for the pressure pin 23 while still permitting proper functioning of the mist trapping shield.

For convenience in assembling the shield 28 in splash pans having inturned lips at the top, the shield, as shown in Fig. 2, may be made in abutting sections 34 of any desired angular extent which closely fit the interior of the pan 11 when assembled together to form the shield. It will be understood that when all the sections 34 have been set into the pan, they position each other correctly and brace each other against displacement. If necessary, recesses 35 may be formed in the adjoining edges of the shield sections 34 so as to clear obstructions such as the supply pipe 19.

As shown in Fig. 1, means are provided for holding the shield 28 in a position above the tool 15, this means comprising a plurality of baffle plates 31 which serve the double purpose of supporting the shield 28 and also reducing the swirling velocity of the mist in the pan. Baffle plates 31 are preferably attached to the shield 28 by screws 32 projecting through holes in the baffle plate extensions 33 underneath the shield. Although baffle plates 31 are shown in radial position, other positions, such as tangential, spiral, or otherwise, are effective for the purpose of this invention so long as the baffles extend across the surface of the shield 28 and stand substantially vertically in the pan 11. Assembly of the shield is very simply accomplished without the use of tools by merely setting the individual sections 34 into place in the pan 11 in abutting relation to each other whereupon satisfactory proper alignment and security of each of such sections is automatically secured.

With reference to the modification of my invention shown in Fig. 3, a mist shield 40 is provided in a form of an annular plate similar to that shown in Fig. 1 but shield 40 is held in position above the surfacing tool by different means. The shield 40 may be constructed as an integral member or may be made in sections of any desirable shape and size for convenience in assembling this device in splash pans having in-turned lips around the upper edge. The supporting means for the shield 40, here shown, consists of a plurality of hooks 41 reaching over the top edge of a splash pan 42 and these hooks are attached to the shield in any suitable manner such as by rivets 43. Alternatively, the shield 40 may be positioned in the pan 42 by other means than the hooks 41, such means being, for instance, a plurality of inwardly projecting studs or shoulders secured to the inside of the pan and bearing against the under side of the shield. Baffle plates 44 are attached to the under side of shield 40 by means of rivets or screws 45.

Assembly of this form of the invention is accomplished by simply inserting the shield 40 in position in the pan 42 and placing the hooks over the upper edge of the pan. In case the shield 40 is composed of sections, each successive

section is hooked progressively onto the lip of the pan as the section is lowered into the pan until the shield 40 is completely assembled. As in the first embodiment of the invention, each of such sections is positioned and braced by its neighboring section.

From the foregoing, it will be seen that I have provided a simple and efficient shield for preventing mist from rising out of the splash pans of surfacing machines, said shields being self-locating and capable of being assembled in operating position without the use of tools, all of which is in accordance with the stated objects of this invention. Although but certain embodiments have been shown and described in detail, it will be understood that these embodiments are not exclusive and changes may be made in the form and arrangement of the parts and substitutions may be made therein without departing from the spirit of the invention as defined in the appended claims.

I claim:

1. A lens grinding machine comprising a vertical, rotatable spindle, a surfacing tool on the upper end of the spindle, a splash pan surrounding the tool, means for supplying a liquid to the tool, means for rotating the spindle at a high speed so that some of the liquid which strikes the tool is atomized, a substantially annular shield horizontally positioned within the pan above the tool for trapping the atomized liquid particles, the central opening in the shield affording access to the tool, and radially disposed spaced baffle plates extending downwardly from the under side of the shield whereby the atomized liquid is trapped and prevented from rising above the shield.

2. In a machine for surfacing lenses and the like having a stationary splash pan surrounding a rapidly rotating tool which is supplied with a jet of liquid coolant, the combination of an annular mist catching shield located contiguous to the inside of the pan in a position higher than that of said tool, said shield being a flat ring constructed in adjoining removable sections, and at least one downwardly extending baffle attached transversely across each of said sections, each baffle resting at its lower edge on the bottom of the pan for the dual purpose of supporting the shield and reducing the swirling velocity of the mist so as to prevent it from rising out of the pan.

HAROLD W. KOSBEE.
